CHURN

Filed May 21, 1929

FIG. 1.

FIG. 2.

Inventor
T.E. Williamson

Watson E. Colenca, ³³⁴

UNITED STATES PATENT OFFICE

THOMAS E. WILLIAMSON, OF KIRKLAND, TEXAS

CHURN

Application filed May 21, 1929. Serial No. 364,869.

This invention relates to the class of churns and pertains particularly to a new and improved churn structure designed for use in association with and to be operated by a washing machine.

The primary object of the present invention is to provide a churn which is adapted to be placed directly in a washing machine of a type employing a series of oscillating stirring fins radiating from an upright post, the churn being formed to receive this upright post and having upon the bottom, clamp members designed to engage the fins or blades of the washing machine so that when the machine is set in motion the churn will be oscillated with the fins. Suitable agitating blades are arranged in the churn so that as the violent oscillating motion of the churn body takes place the contents thereof will be forced back and forth between these blades and thoroughly stirred for the formation of butter.

The invention will be best understood from a consideration of the following detailed description taken in connection with the accompanying drawing forming a part of the present invention with the understanding, however, that the invention is not confined to any strict conformity with the showing of the drawing but may be changed or modified so long as such changes or modifications mark no material departure from the salient features of the invention as expressed in the appended claims.

In the drawing:

Figure 1 is a vertical longitudinal sectional view of the churn embodying the present invention, showing the same applied to the oscillating member of a washing machine;

Figure 2 is a top plan view of the churn with the top removed, a part thereof being shown in section.

Referring more particularly to the drawing in detail wherein like numerals of reference indicate corresponding parts throughout the several views, the numeral 1 indicates the body of the churn embodying the present invention, the same being formed of a cylindrical receptacle having a bottom 2 and an

open top which is normally closed by a lid 3 provided with a suitable handle 4.

This churn is designed to be operated by a type of washing machine wherein is employed within the bowl an oscillating disk 5 carrying a central upright shaft 6, from the lower portion of which, over the surface of the disc, projects a radial series of agitating blades 7. In this type of machine the shaft 6 is connected with certain operating parts so that in the operation of the machine a rapid oscillatory motion of the blades 7 around the shaft center will take place.

The receptacle 1 of the churn has the bottom portion 2 provided with a central opening 8 and within the body is a closed vertically arranged tube 9 which is secured to the bottom over the opening 8 and which is designed to receive the shaft 6 of the machine.

The under side of the churn bottom 2 is provided with a series of resilient clamp members 10 arranged in pairs as shown, each pair of these clamp members being designed to frictionally receive therebetween one of the blades 7 of the machine.

Within the churn body there is secured radially of the bottom a series, preferably four, of dasher blades 11, which blades extend from the sleeve 9 outwardly to a point within approximately one inch of the wall of the receptacle.

Arranged in a plane substantially two inches above the bottom dasher blades 11 is a second series of radially extending blades, preferably three in number, these blades being indicated by the numerals 12. This second series of blades is disposed so that one thereof will be arranged over one of the lower blades 11, while the other two will be disposed between and above a pair of the lower blades in the manner shown.

Arranged above the second series of blades at a point substantially one inch therefrom is a third series of blades, preferably three in number, these blades being arranged in staggered relation with the underlying blades so that none of these three series will be in vertical alignment with the series lying directly therebeneath.

With this arrangement of dasher blades

within the churn body it will be readily seen that when the churn is attached to the machine agitator blades in the manner described and the machine set in motion, the churn will be rapidly oscillated so that milk therein will be dashed between the blades and thoroughly agitated for the formation of butter.

Having thus described my invention, what I claim is:—

- 10 1. A churn of the character described comprising an annular container, a tubular member upstanding in said annular container and opening through the bottom thereof, and a series of radially positioned dasher members secured at one end to the inner periphery of said container and terminating at the opposite end at the tubular member.
- 15 2. A churn of the character described comprising an annular container, a tubular member axially positioned within said container and opening through the bottom thereof, and a series of radially positioned dasher blades positioned in the container, said blades being secured at one end to the container and at the opposite end to the tubular member, each pair of blades being arranged about the tubular member in staggered relation to the adjacent pair whereby to provide a tortuous chamber within the container.
- 20 3. A churn of the character described adapted for use with an oscillating washer comprising a container, an upstanding tubular member axially positioned within the container, means for removably securing said
- 25 container to a washer, a series of pairs of dasher blades radially positioned about said tubular member, said pairs of dasher blades being positioned in staggered relation to each other, and arranged alternately in pairs about said tubular member whereby to provide a tortuous chamber within the container, and a removable cover for said container.

In testimony whereof I hereunto affix my signature.

45 THOMAS E. WILLIAMSON.
